CHEMICAL FIRE APPARATUS.

1,231,272.

Specification of Letters Patent. Patented June 26, 1917.

Application filed March 27, 1917. Serial No. 157,601.

To all whom it may concern:

Be it known that I, FREDERICK H. LANE, a citizen of the United States, residing at Hollis, in the State of New York, have invented certain new and useful Improvements in Chemical Fire Apparatus, of which the following is a specification, reference being had to the accompanying drawing, forming a part hereof.

10 This invention relates to chemical fire apparatus and is concerned primarily with apparatus designed for use in confined or closed places, such as the interior of buildings. More particularly, the invention is

15 concerned with apparatus in which carbon tetra-chlorid, hereinafter referred to simply as tetra-chlorid, is employed as the extinguishing agent and the principal object of the invention is to provide means for

20 applying the tetra-chlorid to the blaze in a more economical, effective and less destructive form than has heretofore been known.

Tetra-chlorid as a fire extinguishing agent has now come into very general use. It is

25 the practice to force the tetra-chlorid in liquid form on to the burning surface and rely on the heat of the blaze to change a substantial portion of the liquid tetra-chlorid into a heavy gaseous blanket which

30 will smother the flames. This evaporation occurs to only a limited degree at the seat of the blaze, remaining in liquid form on the surface, so that for every unit volume of

35 extinguishing liquid evaporated at the seat of combustion, many unit volumes of liquid remain unevaporated. Since the volume of effective vapor created comes from only a small portion of the discharged liquid, it will be evident that a great quantity of

40 liquid must be thrown toward the blaze. This method is very wasteful. Again, it has been found that the application of extinguishing liquids, and particularly tetra-chlorid, to mechanical and electrical ap-

45 paratus generally and to insulation for electric wiring, causes irreparable injury. Since blazes for which chemical fire apparatus is especially suitable are most prevalent about electrical devices, and particularly switch

50 boards, the permanent injury of the equipment by the extinguishing agent becomes a matter of serious moment, especially where the blaze itself is of small consequence. The objections noted to known chemical ap-

55 paratus are sought to be eliminated by the

improvements herein, both in the matter of economy and effectiveness in use without the sacrifice of any of the advantages attendant upon the use of such an agent in liquid form.

In accordance with the invention the extinguishing chemical agent, such as liquid carbon tetra-chlorid, is confined in a suitable reservoir and is forced therefrom under compressed air in the form of a spray 65 through a heating tube in which the vapor is changed into a dry gas, in which form it is directed to the blaze. By applying the agent in gaseous form and at a relatively high temperature, greater economy in the 70 use of the agent itself is achieved since the evaporation is completed entirely before the emission of the gas from the hose nozzle and the enveloping gaseous blanket is directed toward the seat of combustion in a 75 blast so that the blaze is quickly smothered by an inclosing gaseous blanket. Further, and of great importance when the blaze is near electrical equipment or wiring or other apparatus which might be injured by the 80 action thereon of an extinguishing agent in liquid form, this disintegrating or destructive force of the agent is entirely eliminated by applying the agent in a wholly gaseous form. The invention will be set forth in 85 greater detail hereinafter in connection with the description of one embodiment thereof illustrated in the drawing and in which there is shown a portable fire apparatus, parts being broken away to show certain 90 details of construction.

Since it is believed that the present improvements will be of particular importance in apparatus designed for use around electrical equipment, the illustrated embodiment 95 shows suitable portable apparatus which may be used about a building and derive its power either from the supply circuit in the building or from a self contained source. In the drawing the apparatus is shown as 100 mounted on a truck *a* which may carry a storage battery *b* to supply current to an electric motor *c* which is carried on the truck and is connected directly with a blower, the casing of which is indicated by 105 the reference character *d*, the blower and motor being shown in a purely conventional form. Where more convenient, the motor *c* may derive its power from the main supply of the building, a plug connection *e* 110

being provided for association with any available socket terminal. On the truck *a* is carried an air-tight reservoir *f* for the liquid extinguishing agent *g*, which may be carbon tetra-chlorid, and this reservoir may 5 be lined, as at *f'*, with suitable resistant material to prevent disintegration of the reservoir by the chemical. The blower *d* is connected with the upper portion of the reservoir *f* by a pipe *d'*, which may be controlled by a suitable hand valve *d''*, whereby compressed air derived from the blower may be directed upon the surface of the extinguishing agent. From the reservoir *f* the compressed air may pass through a relatively 10 restricted duct *f''* in which terminates a nozzle *h* formed at the upper end of a pipe *h'*, the lower end of which is disposed in the body of the chemical. This construction insures the discharge of the chemical 15 through the duct *f''* in the form of a spray. From this duct *f''* the atomized agent passes through a heating pipe *i* with which is operatively associated a source of heat shown in the drawing as a helical electrical heating coil *k* provided with a plug *k'* at its end by which convenient connection may be made with the source of electricity. In the preferred form of apparatus the motor 20 connections may include a plug *c'* from which current may be led to the plug *k'* of the heating coil. Further, the motor may be provided with a separate plug *c''* for connection, as required, with the battery *b'*. The heating coil *k* just described is 25 preferably inclosed by an insulating casing *l* to confine the heat. From the heating pipe *i* the vaporized chemical in gaseous form is discharged through a flexible hose *m*, made 30 of any suitable material resistant to carbon tetra-chlorid as a chemical agent. This hose may be fitted with nozzles of such construction as to give the most advantageous discharge of the gas according to the 35 conditions of use.

One practicable, simple and compact apparatus for practising the invention has now 40 been described and its purely structural features will be evident. The advance in the art made by the improved apparatus 45 can best be appreciated by a consideration of the mode of use of the improved apparatus and a comparison thereof with the principle on which known extinguishing agents 50 have been applied. Heretofore the extinguishing agents, such as tetra-chlorid, have 55 been discharged from a nozzle in liquid form with the ultimate idea of applying them to the blazing surface in liquid form, from 60 which they would be evaporated by the heat of the blaze and create a vaporous blanket of sufficient density to smother the flame. The liquid thus applied to the seat of combustion 65 is always volatilized imperfectly by the blaze so that the effective gaseous blanket

created by the heat of the blaze has always been small in volume as compared to the total amount of liquid thus applied. Further, the liquid remaining unvolatilized has little, if any, property as an extinguishing agent and 70 so remains on the surface to which it is applied as a deleterious chemical agent. Again, in these known methods of extinguishing, the comparatively strong currents of air created at the seat of the blaze by the heating of the air at that point carry off such gas as is created, thereby defeating to a great extent the very purpose for which the gas is formed, to wit, the smothering of the blaze. Where the extinguishing agent 75 is to be applied in gaseous form, as in the present case, this gas may be directed to a point below the blaze so that as it is carried upward by the rising currents it is carried directly to and about the blaze 80 thereby forming the most effective smothering blanket. Further, where the blaze occurred in the neighborhood of electric wiring, as around switch-boards or the like, the chemical applied has been found to break 85 down the insulation and perhaps otherwise injure the equipment, with the result that more damage is often done by the extinguishing agent than by the blaze itself. By the present improvements these wasteful and 90 injurious methods of applying an agent are overcome. The tetra-chlorid or other chemical is completely gasified in the apparatus before being discharged from the nozzle. The agent is first atomized and, in its 95 vaporous form, is led through a heating coil in which its temperature is raised to a point where a perfect gas is formed and in this heated condition the gas is directed on to the blaze. Since the extinguishing is 100 accomplished by a smothering of the flame, it will be evident that in directing the chemical in gaseous form on to the blaze, an envelop will be created much more quickly and economically than would be possible 105 where the gaseous blanket is formed wholly by the evaporation of the chemical at the seat of combustion. Further, since no liquid is discharged from the apparatus and only a gaseous blanket is placed about the blaze 110 the destructive effects of the chemical by its association with electrical insulation or other equipment in liquid form is entirely eliminated. The extinguishing gas derived 115 from the improved apparatus may be directed against a blaze springing from a surface of any character without danger of injury to the surface by the gas itself. All of the other objectionable results flowing from the application of liquid to a blaze 120 and its neighborhood are also overcome.

A further feature of novelty in connection with the illustrated embodiment of the invention resides in the provision of a bypass *n* from the blower *d* to the heating pipe 125

5 by means of which a current of compressed air may be directed through the hose *m*. While, as described hereinbefore, the extinguishing agent is applied to the blaze in the form of a gas, it will be understood that after the blaze is extinguished and the surfaces to which the gas has been applied cool off, a certain proportion of the gas will be condensed on such surfaces. The objection 10 to the presence of carbon tetra-chlorid in liquid form on surfaces generally and particularly on insulation or other electrical equipment has been pointed out. Accordingly, the blast of air derived through the 15 by-pass *n* is provided so that after the blaze has been extinguished, such a blast may be directed against the surfaces to which the extinguishing gas has been directed for the purpose of completely evaporating any condensed carbon tetra-chlorid that may remain 20 on said surfaces. This blast of air, it has been found, will accomplish this evaporation satisfactorily and completely rid insulation and other electrical equipment to be found 25 around switch-boards of such carbon tetra-chlorid as might remain thereon and injure the same in the manner now characteristic of other apparatus. A further use to which this blast may be profitably put is for the 30 detecting of latent embers. When the blast is applied to such embers sparks will be brought to life and observable. When the by-pass *n* is connected with the heating tube *i*, as indicated in the drawing, this blast may 35 also be used for blowing out any condensed carbon tetra-chlorid remaining in the tube and hose after use of the apparatus so that such liquid tetra-chlorid will not subsequently be deposited on any surfaces. Such 40 a connection also permits the air to be discharged hot or cold, depending upon whether the coil *k* is brought into use or not.

From the description given it will be evident that the apparatus is designed for the 45 application of a chemical extinguishing agent, such as carbon tetra-chlorid, in a wholly gaseous state and that rearrangements of the elements of the apparatus and changes therein in details may be made and 50 the desired results still secured. Further, the invention is not to be limited to a portable apparatus since it is evident that the parts described or their equivalents may be placed in combination in a stationary position. Further, while electricity has been described as being most convenient as a source 55 of power for the driving motor *c* and for the heating coil *k*, it is to be understood that compressed air may be derived from other 60 sources and heating coils of different types may be employed. The appended claims define the scope of the invention.

I claim as my invention.

1. In chemical fire apparatus, an extinguishing chemical agent in liquid form, an

air-tight reservoir for said agent, a source of compressed air, a conduit to lead the compressed air into said reservoir on to the surface of the agent, a discharge nozzle in said reservoir above the surface of the agent, a pipe from the agent discharging into said nozzle whereby the agent is atomized by the compressed air, a heating tube connected with said nozzle to gasify the agent completely and a discharge nozzle through which the agent in gaseous form passes to the blaze.

2. In chemical fire apparatus, an extinguishing chemical agent in liquid form, an air-tight reservoir for said agent, a blower, 80 an electric motor to drive the blower, a valve controlled conduit to lead the compressed air from the blower into said reservoir on to the surface of the agent, a discharge nozzle in said reservoir above the 85 surface of said liquid, a pipe from the agent discharging into said nozzle whereby the agent is atomized by the compressed air, a heating tube connected with said nozzle, an electrical heating coil around said tube to 90 heat and gasify the agent completely and a discharge nozzle through which the agent in gaseous form passes to the blaze.

3. In chemical fire apparatus, carbon tetra-chlorid in liquid form, an air-tight reservoir 95 for said tetra-chlorid, a blower, an electric motor to drive the blower, a valve controlled conduit to lead the compressed air from the blower into said reservoir on to the surface of the tetra-chlorid, a discharge nozzle in 100 said reservoir above the surface of said liquid, a pipe from the tetra-chlorid discharging into said nozzle whereby the tetra-chlorid is atomized by the compressed air, a heating tube connected with said nozzle, 105 the blower, the reservoir and said tube being mounted independently of each other and being formed as separate units, an electrical heating coil around said tube to heat and gasify the tetra-chlorid completely and a 110 discharge nozzle through which the tetra-chlorid in gaseous form passes to the blaze.

4. In chemical fire apparatus, an extinguishing chemical agent in liquid form, an air-tight reservoir for said agent, a source 115 of compressed air, a conduit to lead the compressed air into said reservoir on to the surface of the agent, a discharge nozzle in said reservoir above the surface of the agent, a pipe from the agent discharging into said 120 nozzle whereby the agent is atomized by the compressed air, a heating tube connected with said nozzle to gasify the agent completely, a discharge nozzle through which the agent in gaseous form passes to the 125 blaze, and a valve controlled by-pass from the blower to the heating tube to permit the discharge of a blast of air.

5. In chemical fire apparatus, a portable truck, a reservoir for carbon tetra-chlorid 130

in liquid form carried on the truck, a blower, an electric motor to drive the blower, a valve controlled connection between the blower and the reservoir to lead the compressed air into said reservoir on to the surface of the carbon tetra-chlorid, a storage battery carried on the truck, electrical connections between the motor and the storage battery and between the motor and an external source of current, a discharge nozzle in the reservoir above the surface of the tetra-chlorid, a tube from the tetra-chlorid to said nozzle whereby the compressed air

forces the tetra-chlorid through the nozzle in atomized form, a heating tube connected 15 with said nozzle and carried on the truck, an electrical heating coil disposed about said tube and having connection with any available source of current, a discharge nozzle for the tetra-chlorid gasified in the heating tube, and a valve-controlled by-pass between the heating tube and the blower whereby a blast of air may be discharged.

This specification signed this 22d day of March, A. D. 1917.

FREDERICK H. LANE.
